(57) **CLAIM**

The ornamental design for a multimedia storage support, as shown and described.

DESCRIPTION

FIG. 1 is a front perspective view of a multimedia storage support showing my new design;

FIG. 2 is a front elevational view thereof;

FIG. 3 is a right-hand side elevational view thereof;

FIG. 4 is a left-hand side elevational view thereof;

FIG. 5 is a rear elevational view thereof;

FIG. 6 is a top plan view thereof;

FIG. 7 is a bottom plan view thereof; and,

FIG. 8 is a perspective view similar to FIG. 1, illustrating the way the support can be used for storing CDs, DVDs and/or pockets and casings containing such CDs and DVDs.

The broken lines shown form no part of the claimed design.
